DESIGN FOR A RECEPTACLE FOR FIRE EXTINGUISHING MATERIAL

Andrew Luz, Lowell, Mass.

Application November 16, 1942, Serial No. 108,790

Term of patent 3½ years

To all whom it may concern:

Be it known that I, Andrew Luz, a citizen of the United States of America, residing at Lowell, in the county of Middlesex and State of Massachusetts, have invented a new, original, and ornamental Design for a Receptacle for Fire Extinguishing Material, of which the following is a specification, reference being had to the accompanying drawing, forming part thereof.

Fig. 1 is a front elevational view of a receptacle

for fire extinguishing material showing my new design.

Fig. 2 is a side elevational view,

Fig. 3 is a plan view. A portion of Fig. 3 has been broken away to more clearly illustrate the side panel members.

I claim:

The ornamental design for a receptacle for fire extinguishing material as shown.

ANDREW LUZ.
